CHARLES M. CLARKE, OF ST. LOUIS, MISSOURI

TUBE CLEANER

Application filed June 1, 1931. Serial No. 541,319.

This invention relates generally to tube cleaners and more specifically to tube cleaners of the type which include cleaner or scraping elements adapted to be moved outwardly by centrifugal force, generated by rapid rotation of the device, into scraping contact with the inner faces of the tubes, the predominant object of the invention being to provide an extremely simple device of this type which is 10 so constructed and is capable of such use that the maximum efficiency of operation is realized in the use of the device without danger that damage will be done to the tubes being cleaned.

15 Prior to this invention various types of tube cleaners have been known which performed their function of cleaning tubes with a fair amount of success, but it has been my experience that each of such cleaners with 20 which I am familiar failed to attain complete success in the use thereof because of structural imperfections. For instance some of these previously known tube cleaners failed to be efficient to the maximum degree 25 because they were incapable of completely cleaning the tubes in which they were used, while others thereof produced the maximum cleaning efficiency but did damage to the tubes being cleaned.

30 In view of the foregoing I have devised the improved tube cleaner disclosed herein which briefly stated comprises a head to which a plurality of members are pivotally connected, these members being provided 35 with cleaning or scraping elements. The outer ends of the pivoted members referred to are thrown outwardly by centrifugal force on rapid rotation of the tube cleaner and the cleaning or scraping elements are so located 40 with respect to the length and weight of the pivoted members with which they are associated that said cleaning or scraping elements are caused to contact with the walls of the tubes being cleaned with sufficient force to 45 completely clean the tubes but without doing injury thereto. An important feature of the invention resides in the fact that the cleaning or scraping elements of my improved device are inclined with respect to the longitudinal 50 and transverse axes of the tube cleaner where-

by a shearing action is obtained. Also an important feature of the invention is found in the provision of cutting edges at the forward end of the device whereby the device may cut its way through tubes which are completely closed or substantially so. 55

Fig. 1 is a plan view of the improved tube cleaner.

Fig. 2 is a side elevation of the tube cleaner illustrated in Fig. 1. 60

Fig. 3 is a view of the improved tube cleaner showing same as it will appear when in use within a tube.

In the drawing, wherein is shown for the purpose of illustration, merely, one embodiment of the invention A designates the improved tube cleaner generally. The tube cleaner A includes a head 1 which is provided at its rearmost end with a screwthreaded 65 end of a rod or shaft 3 extended between the tube cleaner A and a suitable motor (not shown) or other motion initiating means. The head 1 is provided with a pair of cavities 4 and 5 which are separated from each other 70 by an integral partition 6 extended longitudinally of the head as shown most clearly in Fig. 3. The cavities 4 and 5 are closed at their rearmost ends by portions of the head 1 and at their inner longitudinal edges by the 75 partition 6, while said cavities are open at their outer longitudinal edges and at the forward ends thereof.

Associated with the head 1 is a pair of members 7 and 8 provided with portions 7' and 8' which are disposed within the cavities 4 and 5 of the head 1. The members 7 and 8 are pivotally connected to the head 1 through the instrumentality of pins 9 and 10 which are extended transversely through the cavities 4 and 5, said pins being passed through apertures formed in the wall portions of the head 1 at opposite sides of said cavities and having their opposite end portions riveted over to secure said pins in place. The pins 85 9 and 10 referred to are extended through openings 11 and 12 formed through the portions 7' and 8' of the members 7 and 8, said openings 11 and 12 being of substantially 90 larger diameter than the pins so that a more 95

or less loose connection is provided between the head 1 and the members 7 and 8.

The portions of the members 7 and 8 located forwardly of the portions 7' and 8' thereof are formed integral therewith, and preferably said forwardly located portions are of slightly greater thickness than said portions 7' and 8', and are of more or less triangular shape. In other words the forwardly located portion of each of the members 7 and 8 is provided with an inner longitudinal face 13 which is substantially parallel with the longitudinal axis of the member, while the outer longitudinal edge face of the member includes a rear portion 14 which is substantially parallel with the longitudinal axis of the member, an intermediate portion 15 which is inclined forwardly and inwardly from said portion 14, and a forward portion 16 which is inclined inwardly from the forward end of the portion 15 to the forward end of the face 13 at an abrupt angle with respect to said portion 15. The precise shape of the forward portions of the members 7 and 8 permit same to swing outwardly in response to centrifugal force within limits without danger of the forward ends of said forward portions striking the inner faces of the tubes being cleaned.

Formed on the members 7 and 8 are cleaning or scraping elements 17 and 18. The cleaning or scraping elements are located at the outer longitudinal faces of the forward portions of said members 7 and 8 and immediately adjacent to rear ends thereof. As shown clearly in Fig. 2 of the drawing the cleaning or scraping elements 17 and 18 are extended transversely of the outer longitudinal faces of the forward portions of the members 7 and 8, but said cleaning or scraping elements are not arranged at a right angle with respect to the longitudinal axes of said members 7 and 8. Instead the cleaning or scraping elements are inclined transversely and forwardly of the outer longitudinal faces of the forward portions of the members 7 and 8 and this arrangement constitutes a very important feature of the invention which will be referred to hereinafter.

On first consideration it may seem that the inclined arrangement of the cleaning or scraping elements 17 and 18 would tend to feed the device through the tube being cleaned as said device is being rotated, but this is not so because of the fact that the oppositely disposed cleaning or scraping elements are inclined in the same direction when the device is viewed as in Fig. 2. In other words the leading end of one of the cleaning or scraping elements as the device is rotated is the forwardly located end of said element, while the leading end of the oppositely disposed cleaning or scraping element is the rearwardly located end of the latter element. From the foregoing it is plain that the tend-

ency for one cleaning or scraping element to feed the device longitudinally of the tube being cleaned is offset by the tendency of the other cleaning or scraping element to feed the device in the opposite direction whereby said device will not be moved longitudinally in either direction by said cleaning elements.

The cleaning element 17 is provided with a scraping edge 17' which is located at the forward face of said cleaning element, while the cleaning element 18 is provided with a scraping edge 18' which is located at the rearward face thereof. The cleaning or scraping elements 17 and 18 extend outwardly beyond the outer longitudinal faces of the pivoted members 7 and 8, and preferably these cleaning elements are formed of hard material suitable for the purpose which is welded or otherwise secured to the members 7 and 8, the latter members preferably being formed of other material. In this manner the necessity to form the members 7 and 8 of the expensive hard material necessary for performing the scraping operations is avoided.

At the forward ends of the members 7 and 8 I weld or otherwise secure cutting portions 19 in place thereon. By so providing the members 7 and 8 with cutting elements at the forward or nose portions thereof the device is caused to cut its way through a tube which is entirely or substantially clogged.

In the use of my improved tube cleaner same is introduced into the tube to be cleaned and the motor which is associated with the tube cleaner is operated so as to subject the tube cleaner to rapid rotation. The result of such rotation will cause centrifugal force to move the outer portions of the pivoted members 7 and 8 outwardly whereby the cleaning or scraping elements associated with said pivoted members will move into contact with the deposit which it is desired to remove from the inner face of the tube. The cleaning device is then moved slowly through the tube, the cleaning or scraping elements 17 and 18 effectively removing all of the deposit from the wall of the tube. Due to the fact that the cleaning or scraping elements are inclined as described a shearing action is obtained which greatly facilitates removal of the deposit from the tube wall. Also, as already explained, the cutting portions 19 at the nose portions of the pivoted members 7 and 8 permits the cleaning device to cut through a deposit by which a tube is entirely or substantially clogged.

It is extremely important to note that the cleaning or scraping elements are located rearwardly a substantial distance with respect to the forward ends of the members 7 and 8. This has the effect of placing considerable weight beyond the cleaning or scraping elements 17 and 18 with the result that

this weight will respond to centrifugal force when the device is rotated in a manner to cause the cleaning or scraping elements 17 and 18 to be moved into contact with the 5 incrusted face of the tube with sufficient force to effectively remove the deposit therefrom and without doing injury to the tube. It is also important to note that the loose pivotal connections between the head 1 and the members 7 and 8 give the device the necessary 10 flexibility to perform its function.

Preferably the outer faces of the cleaning or scraping elements 17 and 18 are inclined inwardly from the scraping edges 17' and 18' 15 thereof so as to provide clearance between said cleaning or scraping elements and the inner face of the tube being cleaned.

I claim:

1. A tube cleaner comprising a head, a 20 plurality of members associated with said head, means for pivoting said members at an end of each thereof to said head whereby the opposite end portions of said members are free to move outwardly in response to centrifugal force generated by rotation of the 25 tube cleaner, and scraping elements associated with said members, said scraping elements being located inwardly a substantial distance from the outer free ends of the pivoted members 30 so as to locate a greater portion of the weight of said pivoted members outwardly beyond the scraping elements.

2. A tube cleaner comprising a head, a plurality of members associated with said 35 head, means for loosely pivoting said members at an end of each thereof to said head whereby the opposite end portions of said members are free to move outwardly in response to centrifugal force generated by rotation of the tube cleaner, and scraping elements associated with said members, said scraping elements being located inwardly a substantial distance from the outer free ends of the pivoted members so as to locate a greater 40 portion of the weight of said pivoted members outwardly beyond the scraping elements.

3. A tube cleaner comprising a head, a plurality of members associated with said head, means for pivoting said members at an end 45 of each thereof to said head whereby the opposite end portions of said members are free to move outwardly in response to centrifugal force generated by rotation of the tube cleaner, and scraping elements associated with said members, said scraping elements being inclined with respect to the longitudinal and transverse axes of said pivoted members and being located inwardly a substantial distance from the outer free ends of the pivoted members so as to locate a greater portion of the weight of said pivoted members outwardly beyond the scraping elements.

4. A tube cleaner comprising a head, a plurality of members associated with said head, 55 means for pivoting said members at an end

of each thereof to said head whereby the opposite end portions of said members are free to move outwardly in response to centrifugal force generated by rotation of the tube cleaner, scraping elements associated with said 70 pivoted members and located at the outer longitudinal faces thereof, and scraping elements at the forward free ends of said pivoted members, the first mentioned scraping elements being located inwardly a substantial 75 distance from the outer free ends of said pivoted members so as to locate a greater portion of the weight of said pivoted members outwardly beyond said scraping elements.

5. A tube cleaner comprising a head, a plurality of members associated with said head, means for loosely pivoting said members at an end of each thereof to said head whereby the opposite end portions of said members are free to move outwardly in response to 80 centrifugal force generated by rotation of the tube cleaner, scraping elements associated with said pivoted members and located at the outer longitudinal faces thereof, and scraping elements at the forward free ends of said pivoted members, the first mentioned scraping elements being located inwardly a substantial distance from the outer free ends of said pivoted members so as to locate a greater portion of the weight of said pivoted members outwardly beyond said scraping elements.

6. A tube cleaner comprising a head, a plurality of members associated with said head, means for pivoting said members at an end of 100 each thereof to said head whereby the opposite end portions of said members are free to move outwardly in response to centrifugal force generated by rotation of the tube cleaner, scraping elements associated with said 105 pivoted members and located at the outer longitudinal faces thereof, and scraping elements at the forward free ends of said pivoted members, the first mentioned scraping elements being inclined with respect to the longitudinal and transverse axes of said pivoted members and being located inwardly a substantial distance from the outer free ends of said pivoted members so as to locate a greater 110 portion of the weight of said pivoted members outwardly beyond said scraping elements.

In testimony that I claim the foregoing I hereunto affix my signature.

ROBERT C. McCACKEN. 120
